WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FINGER FOR LOOM DOBBY.

Application filed March 18, 1926. Serial No. 95,727.

This invention relates to an improved finger for loom dobbies and it is the principal object of the invention to provide a finger of pressed metal having portions of reduced thickness to cooperate with a guiding comb and having other portions hardened to cooperate with the pegs of the pattern chain.

Loom dobbies usually employ a series of harness jacks or levers each of which has connected thereto a dobbay back lever the upper and lower ends of which are each provided with a hook. The hooks are raised or lowered according to the requirements of the pattern by means of so-called dobbay fingers and when lowered cooperate with one or another of oppositely reciprocating knives by means of which the jacks and harness frames are actuated. The fingers are raised by means of pegs on the pattern chain, said pegs entering a groove formed in the bottom of each finger and the dobbay having a guiding comb to hold the grooves in proper register with the pegs. It is a more particular object of my invention to provide a dobbay finger of pressed sheet metal folded on itself and having a guiding wing to cooperate with the comb and having the lower edges thereof hardened to cooperate with the pegs, the inner ends of the fingers being formed as arms for lifting the hooks.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a diagrammatic view taken through a dobbay and showing my improved finger and the associated parts;

Fig. 2 is an enlarged elevation of a dobbay finger;

Fig. 3 is a top plan view of the finger shown in Fig. 2;

Fig. 4 is a plan of the blank for the finger before the same is folded;

Fig. 5 is a horizontal section on line 5—5 of Fig. 2;

Figs. 6 and 7 are vertical sections on lines 6—6 and 7—7, respectively, of Fig. 2;

Fig. 8 is a plan of the bearing forming section located between the folded sides of the finger, and

Fig. 9 is a fragmentary plan view of the 55 comb taken in the direction of arrow 9, Fig. 1 and showing the relation of the separating wings and the dents of the comb.

Referring particularly to Fig. 1 it will be seen that the dobbay comprises a harness jack 20 pivoted on a fixed pin 21 and having attached thereto as at 22 a dobbay back lever 23. The latter has attached to the upper portion thereof a hook 24 which cooperates with a reciprocating knife 25 and has attached at 60 the bottom thereof a second hook 26 which cooperates with a reciprocating knife 27. The knives 25 and 27 are connected so as to work in opposite directions simultaneously and fixed stops 28 engage the upper and lower ends of the levers 23 to limit movement thereof to the left as shown in Fig. 1. The hooks may rest on cross bars 29 when lowered to be engaged by the knives.

A dobbay cylinder 30 is rotatably mounted 75 on a shaft 31 and receives regular intermittent angular movement of such degree that at each pick of the loom a new dobbay chain bar 32 will be brought into operative position with respect to the dobbay finger to be described. Said chain bars are provided 80 with pegs 33 of hardened steel which serve to indicate which hooks are to be lowered into contact wth the knives. A guiding comb C comprises a fixed bar 34 having upwardly 85 extending wires 35 which are spaced apart a distance substantially equal to the thickness of the fingers and the distance between adjacent pegs on the bars 32, as shown in Fig. 9. A rod 36 is provided for supporting 90 the dobbay fingers and upward displacement of the latter is prevented by a rod 37 held in fixed position.

My invention relates to the construction 95 of the fingers F and F' which are raised and lowered according to the location of the pegs 33 and in carrying out my invention I provide a blank 40 of sheet steel or any other suitable material such as shown in Fig. 4, said blank being for the finger F' which 100 raises the upper set of hooks 24. Said blank is provided with a pair of substantially parallel arms 41 and bearing portions 42, said arms and bearing portions being 105 symmetrically disposed with respect to the line of fold indicated by the dot and dash line L in Fig. 4. The other end of said blank is provided with a wing 43 having a

lower straight edge 44 to cooperate with the bar 34 of the comb C. The intermediate portions of the blank are provided with peg runs or arcuate edges as indicated at 45, said edges or runs being flared as shown in Fig. 7 at the time the blank is stamped out.

When the blank 40 is stamped out it is formed so that the arms and the bearing portions are offset from the plane of the blank, 10 the offset being about one-half the thickness of the material as indicated in Fig. 3. As shown in Fig. 4 the offsets for the bearings and arms are supposed to be below the plane of the body of the blank. The wing 43 is 15 separated from the upper part of the blank as shown in Fig. 4 by a narrow slot 46 and said blank is provided with a further slot 47 which extends inwardly from the arms 41 to a point beyond the bearing portions 20 42 said slot facilitating bending of the offset arms. The bearing forming section 48 as shown in Fig. 8 is provided with a bearing portion 49 and an arm 50 similar to the bearing and arm portions of the blank shown 25 in Fig. 4.

In assembling, the blank 40 is folded along the line L, the upper portion being bent forwardly from the position shown in Fig. 4. The wing 43 is not bent but remains as 30 originally stamped to occupy the position shown in Fig. 2 after the folding operation. The center bearing piece 48 is then put in place occupying the space located between the spaced arms 41 and bearings 42, after 35 which the parts are spot welded as indicated at W. The runs 45 will be left in substantial alignment by the folding process with the flared edges forming a groove for the pegs 33. The runs may then be ease hardened 40 to resist wear. The wings 43 are thinner than the total thickness of the finger and cooperate with wires 35 to position the runs accurately with respect to the pegs 33. The flaring of the grooved edges 45 does not extend 45 to the straight edge 44, the latter having parallel sides as indicated in Fig. 3.

The finger F is formed in a manner similar to that described in connection with finger F' with the exception that the arms 50 after being welded are bent upwardly beyond the line of fold L to cooperate with the lower set of hooks.

From the foregoing it will be seen that I have provided a pressed metal dobby finger 55 having the principal portion thereof folded on itself to provide a body portion of increased thickness and weight but having an extending supporting wing of single thickness and that the grooved lower edges of the folded portions are flared to provide a concave run for the dobby pegs, said runs being hardened to resist wear after the welding operation has been carried out. Also it will be seen that the height of the wing is no greater than the width of the blank shown

in Fig. 4 so that no stock is wasted in providing the wing.

Having thus described my invention it will be apparent that changes and modifications may be made therein by those skilled in the art without departing from the spirit and scope of the invention, and I do not wish to be limited to the details herein disclosed but what I claim is:

1. In a loom dobby finger formed of sheet metal, said finger having a body portion folded on itself to form a section of increased width and weight and said finger having a separating wing portion extending beyond the folded portion to serve as a guide, the folded portions having the lower edges thereof flared and hardened to form a groove to cooperate with the pegs of the dobby chain. 75

2. A loom dobby finger formed of sheet metal having a portion folded on itself to be U-shaped in section, a portion of the finger of single thickness of material projecting beyond the folded portion to serve as a guide, and the free lower edges of the folded portion being flared, each flared edge forming with the other a groove for the pegs of the dobby chain. 80

3. A loom dobby finger formed of sheet metal having a portion folded on itself to be U-shaped in section, a portion of the finger of single thickness of material projecting beyond the folded portion to serve as a guide, the free lower edges of the folded portion being flared, each flared edge forming with the other a groove for the pegs of the dobby chain, and bearing portions formed on the folded sides of the blank, said bearing portions being bent into substantial alignment. 95

4. A loom dobby finger formed of sheet metal having a portion folded on itself to be U-shaped in section, a portion of the finger of single thickness of material projecting beyond the folded portion to serve as a guide, the free lower edges of the folded portion being flared, each flared edge forming with the other a groove for the pegs of the dobby chain, and said bent portions having substantially parallel hook lifting arms 110 which are brought into substantial alignment when the first named portion is folded on itself. 115

5. A blank for a pressed metal loom dobby finger, said blank having extending arms and bearing portions and peg run portions all symmetrically disposed about the center line of fold and said blank further having a guiding portion extending on both sides of the line of fold. 120

6. A blank for a pressed metal loom dobby finger, said blank having extending arms and bearing portions and peg run portions all symmetrically disposed about the center line of fold and said blank further having 125

a guiding portion extending on both sides of the line of fold, said lifting arm and bearing portions being offset slightly from the plane of the remainder of the blank.

- 5 7. A blank for a pressed metal loom dobby finger, said blank having extending arms and bearing portions and peg run portions all symmetrically disposed about the center line of fold and said blank further having a 10 guiding portion extending on both sides of the line of fold, said lifting arm and bearing portions being offset slightly from the plane of the remainder of the blank, said blank being slotted along the offset portion 15 from the point adjacent the arm to a point beyond the offset bearing portion.
8. A blank for a pressed metal loom dobby finger, said blank having extending arms

and bearing portions and peg run portions all symmetrically disposed about the center 20 line of fold, and said blank further having a guiding portion extending on both sides of the line of fold, said guiding portion being disconnected from the remainder of the blank on one side of the line of fold. 25

9. A blank for a pressed metal dobby finger having a main portion to be bent on itself along a line of fold, said blank having a guiding wing portions of which extend on both sides of the line of fold and the guiding portion being disconnected from that portion of the blank lying on one side of the line of fold. 30

In testimony whereof I have hereunto affixed my signature.

WALTER H. WAKEFIELD.
